MALINDA EDDIE BROWN, OF PINE BLUFF, ARKANSAS.

BUTTON-FASTENER.

1,032,735.

Specification of Letters Patent.

Patented July 16, 1912.

Application filed February 20, 1912. Serial No. 678,809.

To all whom it may concern:

Be it known that I, MALINDA EDDIE BROWN, a citizen of the United States, residing at Pine Bluff, in the county of Jefferson and State of Arkansas, have invented 5 certain new and useful Improvements in Button-Fasteners, of which the following is a specification, reference being had therein to the accompanying drawing.

10 This invention relates to buttons and the principal object of the same is to provide the button with a novel type of attaching means which is so constructed that the button may be secured to the goods without 15 cutting or tearing the goods and permitting the button to be removed when desired. With this type of securing means the button may be removed and the goods will not be injured.

20 This type of button is very good for use upon buttons which are of such a character that they would be injured by being put in the wash, such as fine pearl buttons, and the like, which are easily broken.

25 This invention is illustrated in the accompanying drawings, wherein:

Figure 1 is a perspective view of the button looking at the inner face. Fig. 2 is a sectional view through the button secured 30 to a piece of goods. Fig. 3 is a perspective view of the clip used in connection with the securing means. Fig. 4 is a plan view of the blank from which the plate portion of the securing means is formed.

35 Referring to the accompanying drawings it will be seen that the button 10 is provided with a neck 11 upon which the plate 12 is secured by means of the rivet 13. The plate 12 is formed from the blank 14, which 40 is shown in Fig. 4. The blank is bent upon the dotted lines 15 to provide overhanging end portions 16, the end portions being provided with tongues 17, thus forming the seats 18. The plate is curved longitudinally, as is clearly shown in Fig. 1 so that 45 the securing clip will be securely held in position. The securing clip shown in Fig. 3 is provided with arms 19 which terminate in outwardly extending feet 20. The clip is 50 formed from resilient metal so that the arms may be pressed in order that the feet 20 may pass beneath the end portions 16.

When using the device the button is placed against the goods 21, and the arms

of the clip are pressed together and inserted beneath the end portions 16 of the plate 12 between the tongues 17. When the clip is released the arms expand and draw the goods beneath the end portions of the plate so that the button will be securely held 55 in position. It will be noted that the clip is of such size that it will fit snugly into the seats 18, and will be prevented from slipping out of the seat by the tongues 7. It should also be noted that by having the 60 plate 12 curved the plate forms a spring so that if the button is used upon a coat which fits tight the coat will fit between the inner face of the button and the portions of the plate which overhang the button, thus 65 securely holding the coat fastened. This device would be of use if the button hole were 70 slightly too large for the button. When it is desired to remove the button so that the button may be used upon another garment 75 or may be removed so as to place the garment in the wash the clip is compressed so that the feet may be withdrawn from beneath the end portions 16 of the plate and the goods can then be withdrawn from under 80 the end portions 16 and the button will be released from the goods. There has thus been provided a simple and efficient device 85 of the kind described and for the purpose specified.

Having thus described the invention, what is claimed as new, is:—

1. A button provided with a neck extending from the inner face, a plate mounted upon said neck, said plate being longitudinally curved and extending beyond said neck, the end portions of said plate being doubled back and positioned in spaced relation above said plate, tongues extending from the ends of said plate, and a clip formed from resilient material having arms adapted to fit and be positioned between said tongues, and provided with feet fitting beneath the end portions of said plate.

2. A button provided with a neck extending from its inner face, a plate secured to said neck, said plate being formed from resilient material, and being longitudinally curved throughout its length, tongues extending from the ends of said plate, the end portions of said plate being bent to form overhanging flanges, and a securing clip fitting beneath said flanges and between said

flanges for connecting a piece of material with said plate.

10

In testimony whereof I hereunto affix my signature in presence of two witnesses.

MALINDA EDDIE BROWN.
